UNITED STATES PATENT OFFICE.

GEORGE F. RICHART, OF GRAND JUNCTION, COLORADO.

VALVE-GEAR.

1,141,416.

Patented June 1, 1915.

Application filed August 7, 1913. Serial No. 788,516.

To all whom it may concern:

Be it known that I, GEORGE F. RICHART, a citizen of the United States of America, residing at Grand Junction, in the county 5 of Mesa and State of Colorado, have invented certain new and useful Improvements in Valve-Gears, of which the following is a specification, reference being had to the accompanying drawings.

- 10 This invention relates to improvements in valve-gears; and an object of this invention is to simplify the construction of valve-gears by doing away with many of the parts of valve-gears now in use.
- 15 Another object of this invention is to provide a valve-gear in which all the parts shall be visible and so positioned as to be easily oiled and accessible for the making of repairs or the replacing of parts.
- 20 A third object of this invention is to provide a valve-gear in which the lead will be increased as the reverse-lever is moved toward the center of its quadrant.

A fourth object of this invention is to 25 provide a valve-gear in which the setting of the valve shall be extremely simple.

In the drawings illustrating the principle of this invention and the best mode now known to me of applying that principle, 30 Figure 1 is a side elevation partly in section of an engine structure equipped with my new valve-gear, so much of the latter structure being shown as is necessary to illustrate clearly this invention; and Figs. 2, 3, and 35 4 are sections on the lines A—A, B—B, C—C, respectively, of Fig. 1.

The drive-wheel *a* is shown as resting upon the rail *b* and as connected through the crank-pin *c* and the main or connecting 40 rod *d* with the crosshead *e*, to which is suitably fastened the outer end of the piston-rod *f* the inner end of which is connected with the piston *g* that reciprocates in the usual way in the steam-cylinder *h*. A steam-chest *i* surmounts the cylinder *h*; and in 45 this steam-chest *i* there travels back and forth a valve *j* the lower end of which controls the flow of steam through the steam-passages *k* and the upper end of which is fastened to a valve-rod *m*.

The lower end of the eccentric arm *n* is mounted free to swing upon the crank-pin *c* and its upper end is connected by the eccentric rod *o* with the upper end of a 50 swinging arm the lead-and-lap lever *p*,

which is pivotally mounted at *q* upon the guide-yoke *r* which connects the crank-ends of the guide-bars *s*, *t*.

Upon the upper guide-bar *s* there is mounted a box *u* in which is journaled a valve-controlling device *v* the upper end of which is connected with the outer end of the valve-rod *m* and the lower end of which is formed with a trunnion *v'* which carries a slide-block *w*. Upon this slide-block *w* there is slidably mounted a link *x* formed near its center with a link-saddle *x'*.

By the lower radius-rod *y* the bottom of the link *x* is connected to the lower end of the lead-and-lap lever *p*, while the top of the link *x* is connected by the upper radius rod *z* to the lower end of a swinging arm known as a motion-arm 2 the upper end of which is journaled in the motion-arm box 3 suitably mounted upon the top guide-bar *s*.

In a suitable journal-box 4 upon the upper guide-bar *s* there is journaled a tumbling-shaft 5 near one end of which there is fastened the lower end of a tumbling-shaft arm 6 the upper end of which is connected by the reach-rod 7 with the reverse-lever 8 the upper end of which may be locked temporarily by the latch 9 with the toothed sector or quadrant 10.

The tumbling-shaft arm 6 is arranged in direct line with the reverse-lever 8. Upon the other end of the tumbling-shaft 5 there is mounted a rocker-arm 11 which is by means of the link-lifting bar 12 connected with the link-saddle *x'*, so that the link is suspended outside of the guides by this link-lifter 12.

The throw of the link *x* is controlled by the lower and upper radius-rods *y*, *z*, which regulate the desired travel of the valve, whether in full gear or short cut-off. Motion for the top of the link *x* is transmitted from the lead-and-lap lever *p* by a motion-rod or link-bar 13 one end of which is connected with the lead-and-lap lever near the top thereof and the other end of which is connected to the motion-arm 2 at the lower end thereof, this same end being connected, as hereinbefore described, with the top of the link by the upper radius-rod *z*.

The setting of this valve-gear is very simple as the lead is given by advanced angularity of the radius-rods *y* and *z*.

The link *x* is raised and lowered through

the tumbling-shaft arms 6 and 11 and the link-lifter 12 by manipulating the reverse lever 8.

The construction of this valve-gear is simple; the crosshead *c* and the main rod *d* are not connected with the valve-gear. All rods are substantially straight and are connected by hardened pins and bushings.

This valve-gear can be used on slide valves or piston valves, as desired, and with inside or outside admission as may be deemed more desirable.

I claim:

1. A valve-gear comprising a link; a pair of swinging arms linked thereto; and an eccentric-rod which controls one of said arms.

2. A valve-gear comprising a link; a pair of swinging arms between which said link is interposed and to which the same is linked; and an eccentric-rod which controls one of said arms.

3. A valve-gear comprising a link; a pair of swinging arms linked thereto and together; and an eccentric-rod which controls one of said arms.

4. A valve-gear comprising a link; a lead-and-lap lever; a motion-arm; a reverse lever which controls said link; radius-rods one of which connects said link and motion-arm and the other of which connects said link and lever; and an eccentric-rod connected to said lever.

5. A valve-gear comprising a link; a valve-rod; a rocking support which carries said link and is connected with said valve-

rod; a pair of swinging arms linked to said link; and an eccentric-rod connected to one of said arms.

6. A valve-gear comprising a link; a pair of swinging arms linked thereto; an eccentric-rod which controls one of said arms; and mechanism for raising said link.

7. A valve-gear comprising an eccentric-rod; a lever which is connected thereto and receives a swinging movement therefrom; a motion-arm which is controlled and rocked by said lever; and a link connected with said lever and motion-arm.

8. A valve-gear comprising an eccentric-rod; a lever which is connected thereto and receives a swinging movement therefrom; a motion-arm which is controlled and rocked by said lever; a link connected with said lever and motion-arm; a rocking support for said link; and a valve-rod connected with said support.

9. A valve-gear comprising an eccentric-rod; a lever which is connected thereto and receives a swinging movement therefrom; a motion-arm which is controlled and rocked by said lever; a link connected with said lever and motion-arm; a valve-rod driven by said link; and means for raising said link on its said support.

Signed at Grand Junction, Colorado, this 31st day of July, A. D., 1913, in the presence of the two undersigned witnesses.

GEORGE F. RICHART.
